APPARATUS FOR GRINDING THE EDGES OF
GLASS PLATES

Lewis Jex-Blake Forbes, St. Helens, England, assignor to Triplex (Northern) Limited, Liverpool, England

Application April 3, 1936, Serial No. 72,513
In Great Britain April 9, 1935

11 Claims. (Cl. 51—101)

This invention has for its object an apparatus for grinding the periphery of a flat glass plate having a plurality of straight sides with rounded corners.

5 In apparatus hitherto employed for this purpose it has been found difficult to secure smooth grinding of the rounded corners, which frequently have a small radius of curvature, at a considerable distance from the point of support 10 of the plate. When such a corner is being ground, the plate has a tendency to chatter against the grinding wheel, with the result that a succession of flat surfaces is produced instead of a smooth uniformly curved surface.

15 In apparatus according to the invention, the edges of plates can be ground smoothly and the grinding pressure is maintained substantially constant, whereby a plate retains the shape to which it was cut.

20 According to the invention, the glass plate is attached to the end of a shaft with the plane of the plate at right angles to the shaft; the shaft is slowly rotated and force is applied to a pivoted arm carrying the shaft to press the edge of the 25 plate towards a grinding wheel, with approximately constant pressure. The means for applying force to the arm may be the weight of the arm with attached parts and the centre of gravity of the arm is then approximately at the level 30 of the pivoting point when the shaft is vertically below the pivoting point on the side of it away from the grinding wheel. A weight on the arm may be adjustable in position to alter the height of the centre of gravity of the arm. The shaft 35 may carry a template adjustable angularly relatively to the glass plate, the template being adapted to abut against a circular or arcual abutment of approximately the radius of the grinding wheel. The shaft may be rotated by a motor 40 and gearing carried on the arm, and means for reversing the direction of rotation of the shaft may be operated by a device on the shaft so that the shaft is rotated forwards and backwards through less than a revolution.

45 In the accompanying drawings:—

Figure 1 is an end elevation of one form of the apparatus;

Figure 2 is a side view thereof;

Figure 3 is a section through the line A—A of 50 Figure 2; with details omitted;

Figure 4 is an end elevation of the upper portion of an alternative form of apparatus, and

Figure 5 is a diagram showing the operative forces.

55 Referring to Figures 1, 2 and 3, the glass plate

1 (shown in dotted lines in Figures 1 and 2) is attached to a frame 2 by the sucker 3. The frame 2 is fixed on the end of a shaft 4 carried in a bearing block 5 (omitted from Figure 3). The bearing block 5 is fixed, by lugs 6, to two channel irons 7, which, by means of bearings 8, are pivoted on the shaft 9 carried in supports 10 on the framework 11. The channel irons 7 thus constitute an arm pivoted at 9 and will herein-after be termed the "pivoted arm 7".

The shaft 4 carries a worm-wheel 12 (Figure 3) driven by a worm on the shaft 13, which is driven by the chain wheel 14 through a worm and wheel in the casing 15 supported on the bracket 16 attached to the bearing block 5. The 15 chain wheel 14 is driven by chain 17 from the motor 18 mounted on the pivoted arm 7. By the above described means the glass plate 1 carried on the lower end of the pivoted arm 7 is slowly rotated. An air passage from the sucker 3 is taken through the collar 19 on the shaft 4 to a pipe 20 which passes up the channel 7 to the 20 exhauster 21 driven by the motor 22, mounted on the upper end of the pivoted arm 7.

An arm 23 is fixed to the right hand channel iron 7 along a line through the pivoting point 9 at right angles to the line joining the point 9 with the shaft 4, and a weight 24 is adapted to slide along the arm 23 and to be fixed thereon in any position. By means of the weight 24 which can be adjusted in height along the left hand channel iron 7, the centre of gravity of the pivoted arm 7, when carrying a glass plate of average weight, is brought to some point on the line of the arm 23, to the right of the pivoting point 9. There is, then, a torque tending to turn the pivoted arm 7 clockwise and thereby to press the edge of the glass plate 1 against the grinding wheel 27. This torque can be adjusted by means of the weight 24, and, whatever the position of the weight 24, the centre of gravity of the pivoted arm 7 is on the horizontal through the pivoting point 9, when the shaft 4 is vertically below this point.

In operation, the glass plate 1 is fixed to the sucker frame 2, so that its centre of gravity is approximately in the line of the shaft 4, and it is slowly rotated by the motor 18 while its edge is pressed against the grinding wheel 27. Thereby its whole periphery, including the rounded corners, is ground.

The pressure between the edge of the plate and the grinding wheel remains substantially constant for all sizes of plates commonly in use provided that the length of the arm from the 55

point 8 to the shaft 4 and the distance of the grinding wheel 27 from the vertical through the point 8 are suitably proportioned to the dimensions of the larger plates of glass to be ground.

8 This will be explained with reference to Figure 5. In this figure, B and C represent the pivoting point 8 and the shaft 4 respectively, and D the centre of gravity of the arm when carrying a plate of average weight. Let l and r be the 10 lengths of the arm BC and BD, and α the angle by which the arm is displaced when a plate with large radius is being ground, so that the points C and D move to positions C' and D'. Let d be the distance of C' from the vertical BC. If W be the weight of the arm (when carrying a plate of average weight) acting at D, the torque exercised is Wr , and when acting at D', the torque is $Wr \cos \alpha$, and $\sin \alpha$ is d/l . If, however, a plate of more than average weight is being ground when the arm is displaced to BC', and the excess weight over the average is w , the torque due to this excess weight is wd . There will then be an increase in torque of $wd - Wr(l - \cos \alpha)$. If the same plate is narrow in 15 width, so that, when its minimum radius is being ground the point C is displaced to C' at a distance of d' from BC, there will be a diminution in torque of $wd' + Wr(l - \cos \alpha)$.

Now let it be assumed, taking conditions found

20 in commerce, that the longest plate to be ground is 100 cm. and that the greatest and least widths of plates of this length are 50 and 25 cm. respectively, these plates having weights of 6 and 3 kg. respectively, and a maximum radius to

25 their rounded corners of 52 cm. in the two cases. The length of the arm BC will be assumed to be 150 cm. The smallest radius to be ground is 25 cm., and the average therefore, 38.5 cm. The grinding wheel 27 should then be 38.5 cm. distant from the shaft 4 when this is vertically below the point 8. That is to say, the distance d and d' , for the two plates considered are both 13.5 cm., and the angle α , when the maximum and minimum radii are being ground, is $5^\circ 10'$.

30 40 The diminution of torque due to the weight W being displaced from D to D' is then $0.004 Wr$, that is to say, a diminution of 0.4% in the pressure between the plate and the grinding wheel.

Now suppose that the smallest plate to be ground 45 is 25 x 25 cm. with weight 0.8 kg. then the average between the largest and smallest plates is 3.4 kg. and the maximum excess over the average is 2.6 kg. The maximum torque, wd , due to this excess is then 35.1 cm. kg.

50 55 Now, a suitable pressure between the plate and the grinding wheel is 8 kg. corresponding to a torque of 1200 cm. kg. When therefore the plate of 100 x 50 cm. has its maximum radius ground, there is an increase of torque of $35.1 - 1200 \times 0.004$ 60 cm. kg. or 30.3 cm. kg., namely $2\frac{1}{2}\%$. When the plate of 100 x 25 cm. has its minimum radius ground, there is a decrease of torque of $17.5 + 1200 \times 0.004$ cm. kg. or 22.3 cm. kg., that is to say, less than 2%. These variations in the 65 grinding pressure are negligible in practice because, if the glass plate be cut to the desired shape, they do not produce any appreciable alteration in the shape. In the above it has been assumed that the diameter of the grinding wheel is sufficient to render negligible variations in pressure due to changes in the point of contact of the plate, with the grinding wheel.

70 The advantage of this construction, with the centre of gravity located as described, may be seen from the fact that, if the centre of gravity

of the pivoted arm were near to the level of the shaft 4, the pressure of the plate on the grinding wheel would vary approximately as the distance of the shaft from the grinding wheel, so that, in the case of the plate 100 x 25 cm. the pressure 5 when the maximum radius was being ground would be some four times the pressure when the minimum radius was being ground.

The length of the arm from the pivoting point 8 to the shaft 4 has only a small effect on the 10 variation in pressure.

The weight 24 may be suspended from an arm 23 having an arcual end, so that the torque exercised by the weight does not vary with the inclination of the pivoted arm 7. In this case, 15 however, the variations in the grinding pressure are slightly greater.

20 Constancy of grinding pressure may be secured by an alternative form of the device shown in Figure 4, which shows only the upper portion of the framework 11 and the pivoted arm 7. The lower portion of the arm 7 is as shown in Figures 1 and 2. The arm 7 is pivoted at 8 to a carriage 25 provided with wheels 26 adapted to run on rails 29 carried on the upper frame 25 member 11. Fixed to the carriage 25 is a nut 30 which engages a screw-threaded rod 31 adapted to be rotated by a motor and gear 32, and provided with bearing 33. A short upward projection 34 on the arm 7 engages a sliding bar 35 by a pin 36 in a slotted hole in the bar. The bar 35 is adapted to slide a short distance in the brackets 37 attached to the carriage 25. The bar 35 has two cam surfaces 38 which engage plungers 39 in switch boxes 40 which constitute 35 a reversing switch in a circuit of the motor 32. In the position shown, neither plunger 40 is depressed, and both switches are open. If, now, the inclination of the arm 7 is increased, the right hand cam surface 38 depresses its plunger 40 to start the motor 32 to turn the rod 31 in a direction which moves the carriage 25, carrying the pivoting point 8, to the right. Thereby the inclination of the arm 7 is diminished until the inclination shown is regained. Similarly, if the 45 inclination of the arm 7 is lessened, the left hand cam surface 38 operates the motor to turn the rod 31 in the opposite direction, and so to, increase the inclination of the arm 7. The device therefore operates to maintain the inclination of the arm 7 constant, by moving its pivoting point 9. 50

55 Now, with the arm 7 shown in Figure 4, which is not counterbalanced and, therefore, has its centre of gravity near its lower end, the pressure of the plate on the grinding wheel 27 is determined by the inclination of the arm. Therefore, as the plate is rotated by the shaft 4, so that the shaft is varying its distance from the grinding wheel, the pivoting point is moved by the device correspondingly, to maintain the inclination of the arm 7, and therefore the grinding pressure, always constant.

60 65 This device, though more complicated than that of Figures 1 and 2, has the advantage that less height is required in the building.

In all the constructional forms of the apparatus, the pivoting point of the arm is preferably so located with reference to the grinding wheel and the shaft that the movement of the shaft, 70 when a plate is being ground, is in a direction which is not far from the centre of the grinding wheel.

75 Some plates have to be ground only round a portion of their periphery, as, for instance, round

three sides and two corners. For grinding such plates, provision may be made to rotate the shaft 4 forwards and backwards instead of continuously in one direction. The left-hand end of 5 the shaft 4 (Figure 2) carries a boss 41, to which a disc 42 is attached. Two lugs 43, which can be fixed to the edge of the disc 42 in any positions, are adapted to strike the lever 44 of a reversing switch 45 in the circuit of the motor 18. By 10 this means the motor 18 rotates the shaft 4 in one direction until the switch 45 is operated by one of the lugs 43; it then rotates it in the opposite direction until the switch is operated by the other lug 43, and so on.

15 When a large number of plates have to be ground to the same shape, it is often convenient to grind them to a template, and the accuracy of the shape is not then dependent on the accuracy with which the plates are cut. The template 20 46 (Figures 1, 2 and 3) is attached to the boss 41 by bolts 47 which pass through arcual slots in the template, so that its angular position relative to the plate 1 may be adjusted. The template 25 46 is adapted to bear against a disc 48 (Figure 3) of the same size as the grinding wheel 21 and pivoted concentrically with the grinding wheel on the support 49. It is not essential that the template should bear against a rotatable disc, and it may bear against a stationary member having 30 its operative portion curved to the radius of the grinding wheel and placed concentrically with the grinding wheel.

The motor 18 is preferably attached to the pivoted arm 1, as shown in Figures 1 and 2, but it 35 may be carried on the framework 11 (or in the case of the construction shown in Figure 4, on the carriage 25) and connected by chain to a chain wheel concentric with the pivoting point 9. The reduction gearing between the motor and the 40 shaft 4 must, however, be carried by the arm, in order to avoid the driving torque of the motor appreciably affecting the pressure of the plate against the grinding wheel. The effect of the 45 driving torque of a high speed motor carried on the framework may be made negligible.

The exhausting means for the sucker may be independent of the arm, and connection made from it to the sucker by flexible tube. Alternatively, the plate may be secured to the end of 50 the shaft by a vent arm and clamp bearing on the outer surface of the plate.

If, in the construction shown in Figures 1 and 2, the weight of the parts carried by the arm is 55 large compared with the weight of the largest plates to be ground, the height of the centre of gravity is only slightly affected by variations in the weights of the plates, but the best result is attained by adjusting the height of the centre of gravity as described above, when the arm is 60 carrying a plate of weight intermediate between the extreme weights of a series of plates to be ground.

Having described my invention I declare that what I claim and desire to secure by Letters 65 Patent is:—

1. Apparatus for grinding the periphery of a flat glass plate comprising, in combination with a grinding wheel, a shaft adapted to be slowly rotated, means for attaching a glass plate to the 70 end of said shaft with the plane of the plate at right angles to the shaft, a pivoted arm carrying the said shaft and adapted to turn in the direction of the plane of the glass plate, speed reduction gear for driving the shaft fixed on the arm, the centre of gravity of the arm with attached

parts being on the side of the pivoting point away from the grinding wheel and approximately at the level of the pivoting point when the shaft is vertically below the pivoting point, and a weight on the arm adjustable in position to alter the height of the centre of gravity of the arm.

2. Apparatus for grinding the periphery of a flat glass plate comprising, in combination with a grinding wheel, a shaft adapted to be slowly rotated, means for attaching a glass plate to the 10 end of said shaft with the plane of the plate at right angles to the shaft, a pivoted arm carrying the said shaft and adapted to turn in the direction of the plane of the glass plate, speed reduction gear for driving the shaft fixed on the 15 arm, a carriage supporting the pivot of the arm and means adapted to move the carriage to maintain the inclination of the arm approximately constant as the distance of the shaft from the grinding wheel varies.

3. Apparatus for grinding the periphery of a flat glass plate comprising, in combination with a grinding wheel, a shaft adapted to be slowly rotated, means for attaching a glass plate to the 20 end of said shaft with the plane of the plate at right angles to the shaft, a pivoted arm carrying the said shaft and adapted to turn in the direction of the plane of the glass plate, speed reduction gear for driving the shaft fixed on the 25 arm, the centre of gravity of the arm with attached parts being on the side of the pivoting point when the shaft is vertically below the pivoting point, a weight on the arm adjustable in position 30 to alter the height of the centre of gravity of the arm, a template attached to the shaft, means for adjusting said template angularly relatively to the shaft and an abutment member presenting a surface of approximately the 35 same radius as the grinding wheel against which the template is adapted to abut.

4. Apparatus for grinding the periphery of a flat glass plate comprising, in combination with a grinding wheel, a shaft adapted to be slowly 40 rotated, means for attaching a glass plate to the end of said shaft with the plane of the plate at right angles to the shaft, a pivoted arm carrying the said shaft and adapted to turn in the direction of the plane of the glass plate, speed reduction gear for driving the shaft fixed on the 45 arm, a carriage supporting the pivot of the arm, means adapted to move the carriage to maintain the inclination of the arm approximately constant as the distance of the shaft from the grinding wheel varies, a template attached to the 50 shaft, means for adjusting said template angularly relatively to the shaft and an abutment member presenting a surface of approximately the 55 same radius as the grinding wheel against which the template is adapted to abut.

5. Apparatus for grinding the periphery of a flat glass plate comprising, in combination with a grinding wheel, a shaft adapted to be slowly rotated, means for attaching a glass plate to the 60 end of said shaft with the plane of the plate at right angles to the shaft, a pivoted arm carrying the said shaft and adapted to turn in the direction of the plane of the glass plate, by a motor and gearing carried by the arm adapted to rotate the shaft, means for reversing the direction of rotation of the shaft, means carried by the shaft adapted to actuate the reversing means to rotate the shaft forwards and backwards through less than a revolution, and means 65

for applying force to the arm to move it to press the edge of the plate against the grinding wheel with approximately constant pressure.

6. Apparatus for grinding the periphery of a flat glass plate comprising, in combination with a grinding wheel, a shaft adapted to be slowly rotated, means for attaching a glass plate to the end of said shaft with the plane of the plate at right angles to the shaft, a pivoted arm carrying the said shaft and adapted to turn in the direction of the plane of the glass plate, by a motor and gearing carried by the arm adapted to rotate the shaft, means for reversing the direction of rotation of the shaft, means carried by the shaft adapted to actuate the reversing means to rotate the shaft forwards and backwards through less than a revolution, the centre of gravity of the arm with attached parts being on the side of the pivoting point away from the grinding wheel and approximately at the level of the pivoting point when the shaft is vertically below the pivoting point, and a weight on the arm adjustable in position to alter the height of the centre of gravity of the arm.

7. Apparatus for grinding the periphery of a flat glass plate comprising, in combination with a grinding wheel, a shaft adapted to be slowly rotated, means for attaching a glass plate to the end of said shaft with the plane of the plate at right angles to the shaft, a pivoted arm carrying the said shaft, and adapted to turn in the direction of the plane of the glass plate, by a motor and gearing carried by the arm adapted to rotate the shaft, means for reversing the direction of rotation of the shaft, means carried by the shaft adapted to actuate the reversing means to rotate the shaft forwards and backwards through less than a revolution, a carriage supporting the pivot of the arm and means adapted to move the carriage to maintain the inclination of the arm approximately constant as the distance of the shaft from the grinding wheel varies.

8. Apparatus for grinding the periphery of a flat glass plate comprising, in combination with a grinding wheel, a shaft adapted to be slowly rotated, means for attaching a glass plate to the end of said shaft with the plane of the plate at right angles to the shaft, a pivoted arm carrying the said shaft and adapted to turn in the direction of the plane of the glass plate, by a motor and gearing carried by the arm adapted to rotate the shaft, means for reversing the direction of rotation of the shaft and means carried by the shaft adapted to actuate the reversing means to rotate the shaft forwards and backwards through less than a revolution, means for applying force to the arm to move it to press the edge of the plate against the grinding wheel with approximately constant pressure, a template attached to the shaft, means for adjusting said template angularly relatively to the shaft and an abutment member presenting a surface of approximately the same radius as the grinding wheel against which the template is adapted to abut.

65 9. Apparatus for grinding the periphery of a flat glass plate comprising in combination with

a grinding wheel, a shaft adapted to be slowly rotated, means for attaching a glass plate to the end of said shaft with the plane of the plate at right angles to the shaft, a pivoted arm carrying the said shaft and adapted to turn in the direction of the plane of the glass plate, by a motor and gearing carried by the arm adapted to rotate the shaft, means for reversing the direction of rotation of the shaft, means carried by the shaft adapted to actuate the reversing means to rotate the shaft forwards and backwards through less than a revolution, the centre of gravity of the arm with attached parts being on the side of the pivoting point away from the grinding wheel and approximately at the level of the pivoting point when the shaft is vertically below the pivoting point, a weight on the arm adjustable in position to alter the height of the centre of gravity of the arm, a template attached to the shaft, means for adjusting said template angularly relatively to the shaft and an abutment member presenting a surface of approximately the same radius as the grinding wheel against which the template is adapted to abut.

10. Apparatus for grinding the periphery of a flat glass plate comprising, in combination with a grinding wheel, a shaft adapted to be slowly rotated, means for attaching a glass plate to the end of said shaft with the plane of the plate at right angles to the shaft, a pivoted arm carrying the said shaft and adapted to turn in the direction of the plane of the glass plate, by a motor and gearing carried by the arm adapted to rotate the shaft, means for reversing the direction of rotation of the shaft, means carried by the shaft adapted to actuate the reversing means to rotate the shaft forwards and backwards through less than a revolution, a carriage supporting the pivot of the arm, means adapted to move the carriage to maintain the inclination of the arm approximately constant as the distance of the shaft from the grinding wheel varies, a template attached to the shaft, means for adjusting said template angularly relatively to the shaft and an abutment member presenting a surface of approximately the same radius as the grinding wheel against which the template is adapted to abut.

11. Apparatus for grinding the periphery of a flat glass plate comprising, in combination with a grinding wheel, a shaft adapted to be slowly rotated, means for attaching a glass plate to the end of said shaft with the plane of the plate at right angles to the shaft, a pivoted arm carrying the said shaft and adapted to turn in the direction of the plane of the glass plate, speed reduction gear for driving the shaft fixed on the arm, and means for applying force to the arm to move it to press the edge of the plate against the grinding wheel with approximately constant pressure, said means for applying force to the arm being the weight of the arm with attached parts, and the centre of gravity of the arm with parts being on the side of the pivoting point away from the grinding wheel and approximately at the level of the pivoting point when the shaft is vertically below the pivoting point.

LEWIS JEX-BLAKE FORBES.
